Frank Beekman

UNITED STATES PATENT OFFICE.

EDWARD H. PARKER, OF WORCESTER, MASSACHUSETTS, ASSIGNOR OF ONE-HALF TO
THOMAS GORE, OF BROOKLYN, NEW YORK.

WIRE STRAND OR ROPE.

1,183,487.

Specification of Letters Patent. Patented May 16, 1916.

Application filed April 16, 1915. Serial No. 21,667.

To all whom it may concern:

Be it known that I, EDWARD H. PARKER, a citizen of the United States, and a resident of Worcester, in the county of Worcester and State of Massachusetts, have invented certain new and useful Improvements in Wire Strands or Ropes, of which the following is a specification.

The present invention relates to wire strands or cables and has for its main object the prolonging of the life of the strand or rope by eliminating the sharp points of contact between the wires and increasing the surface contact therebetween.

Accordingly the invention comprises a strand composed of a center wire having previously formed helical grooves in the body portion thereof and a plurality of outer wires disposed around said center wire and laid helically in the grooves of the center wire.

The invention further consists in a rope or cable made up of a plurality of such strands laid around a suitable core of any character.

In the accompanying drawings the invention is disclosed in a concrete and preferred form but changes of construction may be made without departing from the legitimate and intended scope of the invention.

In the said drawings: Figure 1 is a transverse sectional view through the center wire of a strand. Fig. 2 is a view in elevation of the said center wire. Fig. 3 is a cross-sectional view of a strand embodying the invention. Fig. 4 is a cross-sectional view of a rope or cable embodying the invention.

Similar characters of reference indicate corresponding parts in the different views.

1 indicates a round center wire provided with previously formed helical grooves 2 in the body portion thereof around which are laid a plurality of wires 3, said wires being round and being laid helically in the grooves 2 of the center wire.

By studying the construction shown in Fig. 3 the nature of my invention and its advantage over known forms of strand will be readily understood.

Heretofore in the construction of wire strands the center or forming wire of each strand is round and without any grooves so that the outer wires will make contact with the center wire and with each other at

one point only. Or else the center member 55 is made up of a plurality of specially shaped wires, generally of a flat-like character. In the construction shown in Fig. 3 the helical grooves of the center wire form a bed in which the outside wires are locked by being 60 laid therein and instead of chafing the center wire at one point the wear is distributed over a relatively large area. It will also be observed that since round wires 3 are employed it is possible to lay them by means of 65 bobbins having a planetary motion so that no torsion is imparted to the wires in laying them, and consequently there is no tendency for the wires to untwist.

Such a strand as is shown in Fig. 3 may 70 consist of any number of wires found suitable and a number of such strands may be laid up into a rope or cable having any desired number of strands and having any suitable core. One of said strands may 75 form the core of such a rope or cable but in the form here disclosed there is shown a fiber core 4 with a plurality of strands 5 of the character described laid therearound.

What is claimed, is:

1. A strand composed of a center wire having previously formed helical grooves in the body thereof, and a plurality of outer wires disposed around said center wire and laid helically in the grooves of the center 85 wire.

2. A strand composed of a round center wire having previously formed helical grooves in the body thereof, and a plurality of wires disposed around said center wire 90 and laid helically in the grooves of the center wire.

3. A strand composed of a center wire having previously formed helical grooves in the body thereof, and a plurality of round 95 wires disposed around said center wire and laid helically in the grooves of the center wire.

4. A strand composed of a single center wire having previously formed helical 100 grooves in the body thereof, and a plurality of round wires disposed around said center wire and laid helically in the grooves of the center wire.

5. A stranded rope comprising: a core, 105 and a plurality of strands laid around said core, each strand consisting of a center wire having previously formed helical grooves

- in the body thereof and a plurality of outer wires disposed around said center wire and laid helically in the grooves of the center wire.
- 5 6. A stranded rope comprising: a core, and a plurality of strands laid around said core, each strand consisting of a round center wire having previously formed helical grooves in the body thereof, and a plurality 10 of wires disposed around said center wire and laid helically in the grooves of the center wire.
7. A stranded rope comprising: a core, and a plurality of strands laid around said 15 core, each strand consisting of a center wire having previously formed helical grooves in the body thereof and a plurality of round wires disposed around said center wire and

laid helically in the grooves of the center wire.

8. A stranded rope comprising: a core, and a plurality of strands laid around said core, each strand consisting of a round center wire having previously formed helical grooves in the body thereof and a plurality 25 of round wires disposed around said center wire and laid helically in the grooves of the center wire.

Signed at Worcester, in the county of Worcester and State of Massachusetts, this 30 thirteenth day of April, A. D. 1915.

EDWARD H. PARKER.
